his Attorney.

UNITED STATES PATENT OFFICE.

FRANK DE MINICO, OF NEW YORK, N. Y., ASSIGNOR TO POLLARD-ALLING MANUFACTURING COMPANY, OF NEW YORK, N. Y., A CORPORATION OF NEW YORK.

PRINTING MECHANISM.

1,251,969.

Specification of Letters Patent. Patented Jan. 1, 1918.

Application filed October 28, 1916. Serial No. 128,146.

To all whom it may concern:

Be it known that I, FRANK DE MINICO, a citizen of the United States, and a resident of New York, Bronx borough, in the county of Bronx and State of New York, have invented certain new and useful Improvements in Printing Mechanisms, of which the following is a specification.

This invention relates to printing mechanisms and has for its object to provide, for use in a printing machine having an ink ribbon, a mechanism of the class specified wherein the ink ribbon is fed forwardly for each printing cycle a net amount less than the movement of the printing form, while feeding the ribbon at the speed of the printing form during its engagement therewith.

With these objects in view my improvements comprise means illustrated in their preferred embodiment in the drawing accompanying this specification wherein the figure of the drawing is a diagrammatic side elevation of so much of a printing machine as will suffice to suitably show the essential features of my invention.

Therein a type-form, which may comprise a type-form carrier 2 having a chain of type-form units 3 led therearound, is mounted for rotation on a fixed axis 4. Therebelow platen 5 is pivoted at 6 on arm 7 which swings on fixed pivot 8 remote from pivot 6. Said platen 5 has a downwardly extending arm 9 carrying roll 10 which together with roll 11 also pivoted at 6 engages rotating cam 12 on fixed pivot 13. Rolls 10 and 11 may be urged to engagement with cam 12 by pull spring 14 one end of which is attached to arm 9 and the other end of which engages fixed pin 15.

Type-form carrier 2 may be constantly rotated in the direction of its arrow, or intermittently if desired. The cam mechanism just described is efficient for causing platen 5 to coact in rolling contact with successive type-forms on chain 3 when cam 12 is rotated in the direction of its arrow at a speed four times that of type-form carrier 2, said cam having six lobes while the type-form carrier has twenty-four type-form seats, as 16.

Conveniently led over guide rolls 17 and 18, so as to pass between the type-form carrier 2 and platen 5, is a web of material 19 wound onto roll 20 from supply roll 21.

Rolls 22, 23 engage said web 19 and pay it

out from roll 21 at a speed equal to that of the periphery of type-form carrier 2 during its coaction with platen 5, and roll 20 may be frictionally driven by some well known means not shown, to take up the slack in 60 said web and keep it constantly taut.

Closely above said web 19 and between it and the type-form, ink-ribbon 24 is led in parallelism with said web and in the same direction. Said ribbon may be conveniently 65 stored on supply roll 25 and which roll is preferably under frictional tension tending to retard the paying out of said ribbon. For feeding said ribbon forwardly in the direction of its arrow I provide rolls 33 and 34. 70 For taking up and storing said ribbon 24 I provide roll 26 on fixed pivot 35. Said roll 26 may be frictionally driven by some well-known means not shown, to at one time wind up said ribbon and at another time release 75 it as more fully explained hereinafter. Rolls 33 and 34 are rotated in the direction of their arrows by some well known means not shown, to advance said ribbon at a speed slower than the speed of web 19, 80 whereby a fresh or partially fresh portion of ribbon is presented for each succeeding impression on said web.

However, during the printing operation it is desirable that said ribbon travel at the 85 speed of the web, so that the type-form will make a clear impression and not smudge the web. To this end I provide means comprising a movable member such as roll 27, operable during the coaction of the type-form and platen for paying out stored slack in the ribbon and thereby permitting the ribbon to travel at the speed of the type-form and platen and for thereafter retrieving from roll 26 an equal amount of ribbon 95 after the type-form and platen have relinquished their grip thereon. Said roll 27 may be mounted on the free end of arm 28 and which arm may be pivotally mounted on fixed pin 29. That end of arm 28 opposite roll 27 is connected by link 30 with the outer free end of arm 7, whereby roll 27 is vibrated up and down in unison with the movement of arm 7. At that side of roll 27 opposite roll 33 is mounted roll 32 on a 100 fixed axis and, by passing the ribbon under roll 33, over roll 27 and under roll 32, a certain amount of slack is stored for paying out when required.

It will be understood that during the pay- 110

ing out and retrieving operations rolls 33 and 34 continue to feed ribbon 24 at the slow speed already described, and that the amount of slack relinquished by roll 27 in 5 its downward movement added to the amount fed by rolls 33 and 34, together make up the necessary amount to provide for a ribbon feed, during the coaction of the platen and type-form, equal to the feed of 10 web 19.

In an organized machine embodying my improvements members 2, 12, 22, 23, 33, 34 and the frictional drive of rolls 20 and 26 will be geared together by gearing of well-known character and of such ratios as to 15 produce the timing described.

I claim:

1. In a printing mechanism the combination of a type-form and a platen actuated 20 for intermittent coaction and for forward movement during their coaction, an ink-ribbon between said type-form and said platen traveling in the same direction as said type-form but at a slower speed, and 25 means operable during the coaction of said type-form and platen for paying out said ribbon for permitting it to travel at the speed of the type-form and platen and for retrieving a portion of said ribbon when the 30 type-form and platen have relinquished their grip thereon.

2. In a printing mechanism the combination of a type-form and a platen actuated 35 for intermittent coaction and for forward movement during their coaction, an ink-ribbon between said type-form and said platen traveling in the same direction as said type-form but at a slower speed, and means comprising a movably mounted take-up member whereby slack is maintained in 40 said ribbon between the periods of coaction of said type-form and platen and whereby said slack is paid out for permitting said ink-ribbon to be fed forwardly at the speed of 45 the type-form and platen when gripped between the type-form and platen during their coaction.

3. In a printing mechanism the combination of a constantly traveling type-form, 50 a platen actuated for intermittent coaction with said type-form, an ink-ribbon between said type-form and said platen traveling in the same direction as said type-form but at a slower speed, and means operable during 55 the coaction of said type-form and platen for paying out said ribbon for permitting it to travel at the speed of the type-form and platen and for retrieving a portion of said ribbon when the type-form and platen 60 have relinquished their grip thereon.

4. In a printing mechanism the combination of a constantly rotating type-form, a platen actuated for intermittent coaction with said type-form and during said coaction traveling in the same direction and at 65

the same speed as said type-form, an ink-ribbon between said type-form and said platen traveling in the same direction as said type-form but at a slower speed, and means comprising a pair of members under 70 which said ribbon is led and a third member between said pair of members and over which said ribbon is led and means for moving one of said members, whereby slack is maintained in said ribbon between the 75 periods of coaction of said type-form and platen, thereby permitting said ink-ribbon to be fed forwardly at the speed of the type-form and platen when gripped between the type-form and platen during their coaction. 80

5. In a printing mechanism the combination of a constantly rotating type-form, a platen actuated for intermittent coaction with said type-form and during said coaction traveling in the same direction and at 85 the same speed as said type-form, an ink-ribbon between said type-form and said platen traveling in the same direction as said type-form but at a slower speed, a pair of rolls on fixed axes under which said ribbon is led, a roll mounted between the members of said pair of rolls over which said ribbon is led, and means for moving said roll relatively to said pair of rolls, whereby slack is maintained in said ribbon between the 90 periods of coaction of said type-form and platen and whereby said slack is paid out during the coaction of said type-form and platen, thereby permitting said ink-ribbon to be fed forwardly at the speed of the type-form and platen when gripped between the 95 type-form and platen during their coaction. 100

6. In a printing mechanism the combination of a constantly rotating type-form carrier, a platen actuated for intermittent coaction with said type-form carrier and during said coaction traveling in the same direction and at the same speed as said type-form carrier, an ink-ribbon between said type-form carrier and said platen traveling 110 in the same direction as said type-form carrier but at a slower speed, a pair of members under which said ribbon is led and a third member between said pair of members and over which said ribbon is led and means 115 for moving one of said members, whereby slack is maintained in said ribbon between the periods of coaction of said type-form and platen, thereby permitting said ink-ribbon to be led forwardly at the speed of the 120 type-form and platen when gripped between the type-form and platen during their coaction.

7. In a printing mechanism the combination of a constantly rotating type-form carrier, a platen actuated for intermittent coaction with said type-form carrier and during said coaction traveling in the same direction and at the same speed as said type-form carrier, an ink-ribbon between said 125 130

- type-form carrier and said platen traveling in the same direction as said type-form carrier but at a slower speed, a pair of rolls on fixed axes under which said ribbon is led, 5 a roll mounted between the members of said pair of rolls over which said ribbon is led, and means for moving said roll relatively to said pair of rolls, whereby slack is maintained in said ribbon between the periods 10 of coaction of said type-form carrier and platen and whereby said slack is paid out during the coaction of said type-form carrier and platen, thereby permitting said ink-ribbon to be fed forwardly at the speed of 15 the type-form carrier and platen when gripped between the type-form carrier and platen during their coaction.
8. In a printing mechanism the combination of a constantly traveling type-form, a 20 platen actuated for intermittent coaction with said type-form, an ink-ribbon between said type-form and said platen traveling in the same direction as said type-form but at a slower speed, a pair of members under 25 which said ribbon is led and a third member between the units of said pair of members and over which said ribbon is led and means for moving one of said members, whereby slack is maintained in said ribbon 30 between the periods of coaction of said type-form and platen, thereby permitting said ink-ribbon to be fed forwardly at the speed of the type-form and platen when gripped between the type-form and platen during 35 their coaction.
9. In a printing mechanism the combination of a constantly traveling type-form, a platen actuated for intermittent coaction with said type-form, an ink-ribbon between 40 said type-form and said platen traveling in the same direction as said type-form but at a slower speed, a pair of rolls on fixed axes under which said ribbon is led, a roll mounted between the members of said pair of rolls 45 over which said ribbon is led, and means for moving said roll relatively to said pair of rolls, whereby slack is maintained in said ribbon between the periods of coaction of 50 said type-form and platen and whereby said slack is paid out during the coaction of said type-form and platen, thereby permitting said ink-ribbon to be fed forwardly at the speed of the type-form and platen when gripped between the type-form and platen 55 during their coaction.

10. In a printing mechanism the combination of a type-form and a platen actuated for intermittent coaction and for forward movement during their coaction, means for feeding an ink-ribbon between said type-form and platen in the same direction as said type-form but at a slower speed, and means operable during the coaction of said type-form and platen for paying out said ribbon for permitting it to travel at the speed of the type-form and for retrieving a portion of said ribbon when the type-form and platen have relinquished their grip thereon. 60

11. In a printing mechanism the combination of a type-form and a platen actuated for intermittent coaction and for forward movement during their coaction, means for feeding an ink-ribbon between said type-form and platen in the same direction as said type-form but at a slower speed, means for feeding a web of material between said ink-ribbon and said platen, and means operable during the coaction of said type-form and platen for paying out said ribbon for permitting it to travel at the speed of the type-form and for retrieving a portion of said ribbon when the type-form and platen have relinquished their grip thereon. 70

12. In a printing mechanism the combination of a type-form and a platen actuated for intermittent coaction and for forward movement during their coaction, means for feeding an ink-ribbon between said type-form and platen in the same direction as said type-form but at a slower speed, means for feeding a web of material between said ink-ribbon and said platen in the same direction and at the same speed as said type-form and platen during their coaction, and means operable during the coaction of said type-form and platen for paying out said ribbon for permitting it to travel at the speed of the type-form and for retrieving a portion of said ribbon when the type-form and platen have relinquished their grip thereon. 80

Signed at New York, Manhattan borough, in the county of New York and State of New York, this 27th day of October, 1916, 95 before two subscribing witnesses.

FRANK DE MINICO.
